US0D1109716S

(12) **United States Design Patent** (10) **Patent No.:** **US D1,109,716 S**
(45) **Date of Patent:** **** Jan. 20, 2026**

(54) **AUDIO AND VIDEO APPARATUS FOR REPRODUCING SOUNDS OR IMAGES**

(71) Applicant: **LG ELECTRONICS INC.**, Seoul (KR)

(72) Inventors: **Youngkyoung Kim**, Seoul (KR); **Jaesuk Yoo**, Seoul (KR); **Junghan Ryu**, Seoul (KR); **Myounghoon Kwak**, Seoul (KR); **Youngwook Sohn**, Seoul (KR); **Junhee Yeo**, Seoul (KR); **Sung Gul Hwang**, Seoul (KR)

(73) Assignee: **LG ELECTRONICS INC.**, Seoul (KR)

(**) Term: **15 Years**

(21) Appl. No.: **29/908,216**

(22) Filed: **Jan. 11, 2024**

(30) **Foreign Application Priority Data**

(57) **CLAIM**

The ornamental design for an audio and video apparatus for reproducing sounds or images as shown and described.

DESCRIPTION

FIG. 1 is a front, right side, perspective view of an audio and video apparatus for reproducing sounds or images showing our new design;

FIG. 2 is a rear perspective view thereof;

FIG. 3 is a front view thereof;

FIG. 4 is a rear view thereof;

FIG. 5 is a left side view and a right side view is omitted because it is a symmetrical to the left side view thereof;

FIG. 6 is a top view thereof;

FIG. 7 is a bottom view thereof; and,

FIG. 8 is another front, right side, perspective view thereof, shown in a state of use with the upper speaker protruding upward.

The broken lines indicate portions of the article that form no part of the claimed design.

1 Claim, 8 Drawing Sheets
